UNITED STATES PATENT OFFICE.

CHARLES J. HELLER, OF PHILADELPHIA, PENNSYLVANIA.

DESIGN FOR A HAT.

SPECIFICATION forming part of Design No. 17,710, dated September 13, 1887.

Application filed May 2, 1887. Serial No. 236,889. Term of patent 14 years.

To all whom it may concern:

Be it known that I, CHARLES J. HELLER, a citizen of the United States, residing at Philadelphia, in the county of Philadelphia and State of Pennsylvania, have invented and produced a new and original Design for Police Hats, of which the following is a specification, reference being had therein to the accompanying drawings, forming part thereof.

10 Figure 1 is a side elevation of my newly-designed hat, and Fig. 2 is a front end elevation, these two views being deemed necessary to fully illustrate my design.

Heretofore the class of hats to which my design relates—viz., police or helmet hats—have a design of brim which is called a “dishing-shaped” brim; but as usually made the angle between the crown and the brim is the same all the way around the hat or at the ends and sides. 15 This sameness of angle gives too much dish to the brim and makes the hat look unsightly, besides which the width of the brim at the back of the hat is made smaller than that at the front of the hat.

20 The leading feature of my design consists of a brim having an equal width or depth back and front, and the brim is so joined to the crown of the hat that the angle of junction between said parts at the front and back is equal, 25 while from said points around to the sides said angle varies or is different from and less obtuse than the angle at the back and front. This variation in the degree of the angle, as aforesaid, admits of a shallower dishing shape for 30 the brim, the sides of which have graceful

curves, as shown, to make a very slightly and desirable shaped hat of the kind illustrated in the drawings.

A represents the crown of the hat; B, the brim, the front and back ends, b and b', respectively, of which are of equal width; and C C and D D, the angles at the ends and sides of the brim with the crown, respectively.

The angles C C are equal, as also are the angles D D; but the latter are different from 45 or less obtuse than the former, and between these angles around the hat the junction angle continuously varies.

What I claim is—

The design for a police or helmet hat herein 50 described and shown, the same consisting of a rounded crown, A, and dishing shaped rim B, the back and front of which are of an equal width, and the angle of junction between the crown and rim at the front and back is equal 55 or the same, the angle of junction of said parts at the sides is also equal but of a lesser obtuse angle than that at the front and back, and the angle of junction for said parts from the greater obtuse angles at the front and back to 60 the lesser obtuse angles at the sides varies gradually to meet said greater and lesser obtuse angles, as set forth.

In testimony whereof I affix my signature in presence of two witnesses.

CHARLES J. HELLER.
